US00D965967S

(12) United States Design Patent (10) Patent No.: US D965,967 S
(45) Date of Patent: * Oct. 11, 2022

(54) SOCK

(71) Applicant: Arebesk Inc., Los Angeles, CA (US)

(72) Inventor: Leana P. Shayefar, Los Angeles, CA (US)

(73) Assignee: Arebesk Inc., Los Angeles, CA (US)

() Term: 15 Years

(21) Appl. No.: 29/770,395

(22) Filed: Feb. 11, 2021

(51) LOC (13) Cl. 02-04

(52) U.S. Cl.

USPC D2/994

(58) Field of Classification Search

USPC D2/980-994

CPC A41B 11/00

See application file for complete search history.

(57) CLAIM

The ornamental design for a sock, as shown and described.

DESCRIPTION

FIG. 1 is a perspective view of a sock in use, showing the new design;

FIG. 2 is a top view thereof;

FIG. 3 is a bottom view thereof;

FIG. 4 is a side view thereof;

FIG. 5 is a front view thereof; and,

FIG. 6 is a rear view thereof.

The broken lines shown are included only for the purpose of illustrating environmental subject matter, and form no part of the claimed design.

The dot-dash broken line depicts a break line that forms no part of the claimed design.

1 Claim, 3 Drawing Sheets
